Inventor.

F. S. Bennett

United States Patent Office.

ERASTUS S. BENNETT, OF NEW YORK, N. Y., ASSIGNOR TO HIMSELF AND JUSTUS SMITH, OF SAME PLACE.

Letters Patent No. 86,126, dated January 26, 1869; antedated January 21, 1869.

IMPROVEMENT IN SAFETY-VALVES.

The Schedule referred to in these Letters Patent and making part of the same.

To all whom it may concern:

Be it known that I, ERASTUS S. BENNETT, of the city, county, and State of New York, have invented a new and useful Improvement in the Construction of Safety-Valves; and I do hereby declare that the following is a full and exact description thereof, reference being had to the accompanying drawings, and to the letters of reference marked thereon.

The nature of my invention consists in the method of constructing a safety-valve and low-water indicator, and the combination therewith of a device or devices, by means of which low water or high pressure is made to open the furnace-door or doors, open a supplemental outlet for steam, close the damper in the chimney, or smoke-stack, ring a bell in any part of the building or vessel, and blow an alarm-whistle, all automatically, so that ample warning of approaching danger from either "high pressure" or "low water" is given, and the remedies or preventives applied instantly, automatically, and effectually.

To enable others skilled in the art to make and use my invention, I will proceed to describe its construction and operation.

Figure No. 1 represents the line view of a half section of my valve and combinations.

B, a weight, composed of a number of metallic plates, which vary in thickness, and are provided with a hole in the centre, through which the valve-stem C passes, on which they are secured by the nut D.

E E, the valve.

F F, its jacket.

G G, openings in said jacket,

H H, passages for escaped steam.

I I, casing for valve-jacket, supplied at the top with a short flange, by which it is fastened to the plate A A.

At the bottom of the casing the plate J J is fastened. Said plate is a rest for the valve E E, and its jacket F F, and guide for the valve-stem C. It is supplied also with a supplemental guide, and furnishes the fulcrum for the float-arm 13; the holes K K allowing the steam free admission to the interior of the valve.

M, an ordinary steam-whistle, communicating with one of the steam-passages H, and directly with the boiler, by means of the branch-pipe W, (dotted lines,) which pipe is furnished with a cock, so that steam may be made to blow the whistle independently of the passage H, when desired.

N N, a cylinder, communicating, by means of the pipe O O, with the other passage H.

P, its piston.

Q, its piston-rod.

S, a block fastened to the outer end of the piston-rod, and made by it to move on the slide R.

The dotted lines T T T, show connecting-rods, by means of which, when the piston is pushed out, the damper U in the smoke-stack is closed, the outlet V

is opened, the bell 16 is rung, and the furnace-door is opened, (17.) Any simple device at the end of the rod, may be used for this latter purpose. I have shown in 17, a wedge, which being pulled over a pin, 18, raises the latch.

L, a hollow metallic float.

13, its arm.

4, knuckle-joint.

5, fulcrum.

Figure No. 2, bottom view of plate J J, showing openings K K, fulcrum 5, and supplemental guide 20, by dotted lines.

C, hole for valve-stem.

Figure No. 3, top view of valve E.

Y Y Y, holes through the large or lower portion of the valve.

Figure No. 4, top view of valve-jacket F F in its case I I, showing passages for escaped steam H H and 6 6 6 6, lugs 3 3, and projections 2 2 2.

Figure No. 5, top of plate A A, showing slides R R, bed-pieces X X for cylinder, passages for escaped steam 6 6 6 6, the hole 7 connecting the cylinder N N, by means of the pipe O O, (Fig. No. 1,) with the steam-passage H, (figs. 4 and 7;) and the hole 8 connecting the whistle M by means of pipe, with the other steam-passage H, (figs. 4 and 7.) The top of lugs 3 3 is also seen in this figure.

Figure No. 6, a perspective of the whole, minus the connecting-rods and their appurtenances. (These must be of size and shape to suit various cases. See Fig. No. 1.)

B, weight.

L, float.

13, float-arm.

4, a knuckle-joint in said arm.

5, its fulcrum.

I, casing.

A, plate.

M, whistle.

W, its separate connection with the boiler.

R, slides.

S, sliding block.

Q, piston-rod.

N N, cylinder.

3 3, lugs, (shown in fig. 7.)

6 6 6 6, openings for escaped steam.

Figure No. 7, perspective of the valve-jacket F, (Figs. No. 1 and 4.)

2 2 2, projections, which, fitting tightly into corresponding grooves in the casing I I, form the separate passages H H. The openings G G are also seen in this figure. They are six in number, four large and two smaller ones. The flange at the bottom is intended, in connection with the plate J, (Fig. No. 1,) to form a tight joint with the case I I.

Return to Fig. No. 1. The piston P and valve E are

made steam-tight by means of suitable packing, at 9 9 9 9. The steam has at all times a free access to the space 10, but cannot pass into space 11, so that in space 11 there can be no pressure. (A small hole in the cap 12, provides for any slight leakage.) Hence, the upward pressure is in proportion to the size of the upper space, or the diameter of the upper portion of the valve, independently of the size of the lower part.

The mode of operating the valve is quite simple. The weight B is adjusted to the diameter of the upper part of valve E E, and the desired amount of pressure, by adding to (or removing) plates from the weight. When the pressure exceeds the amount to be allowed, it raises the valve E E, and steam, passing through the openings G G to the passages 6 6 6 6, escapes to the open air, and through H H to the cylinder and whistle, so that said whistle is blown and the piston pushed outward at the same time. When the piston-rod is pushed out, it being connected, at T, with the damper in the smoke-stack, it closes it; another or the same connecting-rod opens the valve V, and permits steam to escape from the boiler through the pipe X; another or the same rod, or a branch of it, T, leads to the furnace-door 17, and opens it. A wire, attached at any suitable point to either of the connecting-rods, is made to ring a bell, 16.

The pump may be set in motion by the same means, and the grate-bars let down, if desired.

The whole is operated in the same manner, by means of low water in the boiler.

The float opens the valve by means of its arm 13 and fulcrum 5, acting on the stem C, when the water reaches "low-water line." High water does not affect the valve, owing to the knuckle-joint 4.

The position of the float may be adjusted to the low-water line by bending the arm 13, or by a set-screw in the lower side of the knuckle-joint.

The whistle is operated separately from the valve, as a signal, by opening the valve 2 2 in the pipe W.

What I claim as my invention, and desire to secure by Letters Patent, is—

1. The arrangement of the float L, adjustable weight B, valve E, and outlets H H and 6 6 6 6, substantially as described.
2. The combination of the cylinder N, piston Q, and connecting-rods T T, with a safety-valve, substantially as described.

E. S. BENNETT.
